UNITED STATES PATENT OFFICE.

J. HENRY CARVER, OF PHILADELPHIA, PENNSYLVANIA.

CAR-STEP.

SPECIFICATION forming part of Letters Patent No. 299,959, dated June 10, 1884.

Application filed March 8, 1884. (No model.)

To all whom it may concern:

Be it known that I, J. HENRY CARVER, a citizen of the United States, residing at Philadelphia, in the county of Philadelphia and State of Pennsylvania, have invented a new and useful Folding Step for Cars, of which the following is a specification.

My invention relates to an improvement in car-steps, whereby an additional step is secured to the car, and, when not in use, is made to fold beneath the one to which it is attached.

The object of my improvement is to provide an additional or folding step which can be readily worked from the platform, and which, when not in use, will not extend below the regular steps of the car. I attain this object by the mechanism illustrated in the accompanying drawings, in which—

Figure 1 represents the step as it appears when down and ready for use. Fig. 2 is a side view of the mechanical contrivance and step when down and ready for use, as in Fig. 1. Fig. 3 is a similar view of the mechanical contrivance and step when the latter is folded and not in use. Fig. 4 is a rear view of the mechanical contrivance and step when the latter is unfolded or down, as in Fig. 1. Fig. 5 is a small spring-brake which acts against the handle or rod, as hereinafter described. Figs. 6 and 7 show the staple or hinge to which the swinging supports are attached. Fig. 8 is a spring which acts upon the handle or rod, as herein-after described. Fig. 9 is the rear brace or support adjusted to the folding step and made to catch or hook in a corresponding catch or hook adjusted to the step from which the folding step is suspended.

The step A is supported at the sides by the swinging pendants B B, and when in position for use is made firm by the rear support, C, which, with the catch D, is made to drop or fasten in a corresponding catch, E, the catch E being adjusted to the rear of the step from which the folding step is suspended, as aforesaid.

F is a rod or bar attached by a hinge or similar contrivance to the rear support, C, and G is

attached to F in like manner, the said G being a crank, and terminating in a smaller crank, H, to which the handle or rod I is adjusted, the said handle or rod to pass through or above the platform, so that when let or forced down it acts upon the cranks H and G, which in turn act upon the rod F, which, being attached to the support C, raises the step or lets it down, allowing the hook or catch D to drop into the corresponding hook or catch, E, affixed to the permanent step. The handle or rod I is held up, which closes the step C by the spring J, or, if there be no spring J, by the brake K, and when let or pressed down, which unfolds or forces the step C out, is held in that position by the said brake K, the handle or rod I having certain notches, into which the brake K enters, thereby holding the handle or rod I firmly, whether the same be up or down. The handle or rod I is to be operated by the hand, by a lever, by foot-pressure, or other method, vertically, horizontally, or otherwise, as may be deemed most expedient.

I therefore claim as my invention and desire to secure by Letters Patent—

1. The combination, with the permanent car-steps, of the folding step A, supported at its sides by the swinging pendants B B and from the rear by a brace or fixture, C, said brace or fixture having its upper end arranged with a hook or catch to engage with a corresponding hook or catch, E, on the rear of the step from which the folding step is hung, substantially as and for the purposes set forth.

2. The combination of the brace C, furnished with a hook or catch, as described, rod F, crank G, crank H, rod I, folding step A, and permanent steps, all arranged substantially as described.

3. The herein-described device for raising and sustaining the rod I, consisting of the spring J, or its equivalent, substantially as set forth.

J. HENRY CARVER.
